(Cl. D62—4)

To all whom it may concern:

Be it known that we, Conrad J. Oliver and Joseph Kupski, both citizens of the United States, and residents of the city of Waukegan, in the county of Lake and State of Illinois, and of the city of North Chicago, in the county of Lake and State of Illinois, have jointly invented a new, original, and ornamental Design for an Electric Hand Drier or Similar Article, of which the following is a specification, reference being had to the accompanying drawing, forming a part thereof.

On the drawing:

We claim:

The ornamental design for an electric hand drier or similar article, substantially as shown.

CONRAD J. OLIVER.
JOSEPH KUPSKI.
